HANGER FOR FRAMES AND THE LIKE

Filed Nov. 30, 1926

UNITED STATES PATENT OFFICE

JOSEPH A. HOEGGER, OF JERSEY CITY, NEW JERSEY

HANGER FOR FRAMES AND THE LIKE

Application filed November 30, 1926. Serial No. 151,644.

My invention relates to an improved means for hanging mirror frames, pictures frames, panels, plates and similar things, in such a way that the supported articles will lie flat against their support, and also in such a way that the hanging means is concealed by the article which is hung. My invention is intended to produce a simple and very strong hanging means which is entirely out of sight, and which will permit the article to be suspended to lie flat against its support, and to construct the hanging means so that it is a very easy and simple matter to hang the desired article or to remove it from its support. My invention is also intended to provide a structure which serves as a hanger and which can be easily adjusted to fit articles of different sizes.

Reference is to be had to the accompanying drawings forming a part of this specification, in which similar reference characters indicate corresponding parts in all the views.

Figure 1 is a broken front elevation of the structure embodying my invention, showing by full lines its application and by dotted lines an extended position of one of its connected ends.

Figure 2 is a vertical longitudinal section on the line 2—2 of Figure 1.

Figure 3 is a broken enlarged detail view of a part of the hanger.

Figure 4 is a vertical section on the line 4—4 of Figure 3, and

Figure 5 is a broken sectional plan of a part of the hanger.

In the drawings 10 represents a support which may be a flat wall, and 11 a conventional frame which is represented as a mirror frame having a glass 11', but so far as the invention is concerned the frame may be any type of frame having a flat back or essentially flat back, or a plate, panel, or similar structure. To the support is transversely attached a plate or strap 12 which can be conveniently be of sheet metal, and which has

near the end portions sockets 13 formed by pressing out the metal, and these are provided with slots 14 extending through their walls. To the frame 11 or to any other article similar to a frame, are attached 50 brackets 15 being placed opposite each other on the back of the frame, and these are provided with tongues 16 which are adapted to enter the sockets 13, and which near their free ends are preferably bent to form bosses 55 17 which will project into the slots 14, as shown clearly in Figure 4, so that when the tongues are dropped into the sockets, the bosses 17 will offer sufficient resistance to prevent the tongues from being too easily removed, and yet they will permit the tongues 60 to be removed if sufficient force is applied to raise the frame and tongues.

The structure already defined is sufficient for most purposes and for frames, plates, 65 panels, or the like, which are not very large. The plate 12 is fastened to the wall, the brackets 15 to the frame or similar thing, and then the frame is raised so that the tongue 16 will be above the sockets 13 and will 70 register therewith, after which the frame is moved downwardly flat against the wall and the tongues enter the socket and support the frame.

If, however, the frame is large or it is desired to secure it more firmly than in the manner above described, I provide a similar fastening for the bottom. To this end the plate 12 can have a downwardly extending adjustable tongue or extension formed of the 75 80 overlapping parts 18 and 19 which are slideable one on the other, and as shown they are guided by clips 20 on the part 19 which overlap the member 18. The head 21 on the member 18 prevents the parts from being entirely 85 separated. The lower end of the member 19 has a socket 22 like the sockets 13 already described, except that it is open at the bottom. This is adapted to receive the tongue 23 90 which is attached to the back middle por-

tion of the frame 11 or other analogous structure, and the tongue is adapted to enter the socket 22.

When the extension of the plate 12 is used, 5 it is adjusted to the right length and fastened to the wall or support, and when the frame is hung the tongue 23, which can have some flexibility, is guided into the socket 22, and the frame raised until the tongues 16 10 are shown above the sockets 13, when the frame may be pushed back against the wall and dropped. The tongue 16 will thus enter the sockets 13, but the tongue 23 is long enough so that it will not be removed from 15 the socket 22, and thus the frame will be supported by the tongues 16 and the plate 12, but will be braced and guarded against lateral movement by the tongue 23 and socket 22.

It will be seen that the structure shown can 20 be very cheaply and yet strongly made, that it can be easily applied to a wall, and that by the use of the hanging mechanism described, any flat backed object can be quickly and securely mounted or hung.

25 I claim:—

1. The combination with a wall supported element having longitudinally and transversely extended portions each provided with sockets, of a plurality of hangers adapted 20 to be secured to the rear of an article and removably engageable in the sockets in said wall supported element, the said portions and hangers being located relative to each other when in engagement one with the other 25 to be concealed by the article, one of the portions of the wall supported element being adjustable relative to the other portions thereof.

2. The combination of a frame, a plurality 40 of brackets carried at the back of the frame in spaced relation to each other and forming tongues, a strap adapted to be transversely attached to a support and having sockets therein remote from each other for the detachable engagement of the tongues of a pair 45 of brackets therein, and an extensible member fixed to the strap and having a socket for the engagement of the tongue of the other bracket therein when said member has been 50 extended.

3. The combination of wall supported and frame carrying elements, the wall supported element being socketed and tongues on the frame carrying elements for removable engagement in the sockets in said wall element, 55 one of the tongues being disposed in a direction toward the other tongues on the frame carrying elements, and a displaceable part coacting with the wall supported element for the adjustment thereof relative to the tongues of the frame carrying elements.

4. A hanger of the kind described comprising a T-shape supporting element having its stem portion extensible and vertically arranged, 65 said member being adapted for at-

tachment to a wall and with the arms provided with sockets on opposite sides of the stem and opening upwards, and the stem provided with a downward opening socket at its lower portion, and tongues adapted to be secured at desired positions to the article to be supported, said tongues being adapted to register with the aforesaid sockets.

In testimony whereof, I have signed my name to this specification this 29th day of Oct., 1926.

JOSEPH A. HOEGGER.
